JOHN F. LAPLACE, OF HAMBURG, CONNECTICUT.

Letters Patent No. 78,815, dated January 28, 1868

IMPROVEMENT IN BEARING FOR SHAFTS

The Schedule referred to in these Letters Patent and making part of the same.

TO ALL WHOM IT MAY CONCERN:

Be it known that I, JOHN F. LAPLACE, of Hamburg, in the county of New London, and State of Connecticut, have invented a new and improved Bearing for Shafts; and I do hereby declare that the following is a full, clear, and exact description thereof, which will enable others skilled in the art to make and use the same, reference being had to the accompanying drawings, forming part of this specification, in which—

Figure 1 represents a vertical central section of my invention.

Figure 2 is an inverted plan view of the same.

Similar letters of reference indicate like parts.

This invention relates to a new device for supporting the ends of vertical and inclined shafts, and of such horizontal shafts which are arranged in vessels, and which are, by the rocking motion of the vessel, liable to be thrown into an inclined or vertical position.

The invention consists in the use of a series of balls, which are arranged between two disks, and at equal distances from the axis of the shaft. One of these disks is secured at or near the end of the shaft, to the latter, while the other is firmly secured to a stationary bed. As soon as the shaft is revolved, the disk at its lower end will be carried around with it, and the balls which sustain the whole weight of the shaft will revolve around their own axis, and also around that of the shaft. By the application of the balls the friction produced at the lower end of the shaft will be greatly reduced.

A represents a vertical shaft, of suitable construction and arrangement. B is a disk or plate, mounted at or near to the lower end of the shaft, and at or near the upper end of the same, as may be desired. It is made in form of a dish, that is, it is provided with a projecting rim, *a*, as is clearly shown in fig. 1. C is a disk or plate, which is arranged stationary below the disk B, being supported by suitable substantial foundations or bed-plates. D D are balls, which are arranged between the disks B and C. E is a perforated plate, which is arranged around the shaft A, and within the flange *a*, being held in a groove, formed in the inner side of the flange, as shown in fig. 1, the said plate being held so that it can freely turn in the rim *a*. The balls fit through the holes in the plate, and are thereby held the proper distance apart from each other, and form the axis of the shaft A. By removing a ring, *b*, which is secured in the flange *a* by means of pins or screws *c*, the plate E can be easily taken out. Instead of being arranged as shown, the flange *a* and its appendages may also be secured to the stationary disk, instead of to the revolving disk, and the revolving disk may be arranged below or above the stationary disk, according to the position of the bearing on the shaft.

What I claim as new, and desire to secure by Letters Patent, is—

1. The perforated plate E, carrying the balls D, when such plate is arranged to turn loosely in the groove, constructed as described, in the flanges *a* of the disk, as herein set forth, for the purpose specified.
2. The disk B, constructed as described, bearing the perforated plate E, held in place by the ring *b* and pins *c*, in combination with the balls D, shaft A; and stationary plate C, as and for the purpose specified.

JOHN F. LAPLACE.
